poration of Massachusetts

Application September 10, 1952, Serial No. 308,816

2 Claims. (Cl. 139—232)

1

This invention relates to improvements in a multiweft or multicolor weft replenishing loom and it is the general object of the invention to provide improved means for placing the bobbins of several different stacks in position for transfer into a shuttle.

Multicolor weft replenishing looms of the type capable of supplying more than two different kinds of weft have generally been made with the bobbins arranged in vertical stacks in a stationary magazine wherein the bobbins when released from their respective stacks fall to a common transfer position. In this type of magazine the bobbin which is released from a stationary stack falls along guides to the transfer position and is not positively moved to that position.

It is an important object of the present invention to provide a multistack weft replenishing mechanism including several reserve bobbin magazines each capable of moving from a normal position to a position in which the lowest bobbin in discharge position with respect to the magazine will be located at a common transfer point. With the magazines mounted in this manner the bobbin to be transferred irrespective of the magazine in which it is located will be positively moved to the common transfer position in readiness for transfer into a depleted shuttle.

It is a further object of the invention to provide the replenishing mechanism with pivotal supports for the several magazines, these supports being so located with respect to each other and their corresponding magazines that all of the magazines can be moved independently of each other to locate their lowest bobbins in transfer position.

It is a further object of the invention to make each magazine of a single stack type and arrange them in back and forth order in the loom and pivot the frontmost and rearmost magazines about a common axis and pivot the other magazines between these two on separate centers.

It is a still further object of the invention to provide an improved form of selectively controlled actuator for the operating mechanism of the magazines so that the latter can be operated one at a time. In this feature of the invention it is a still further object to make the operating mechanisms for the several magazines in such manner that they tend to return their respective magazines to normal position but will yield to take up any excess motion of the actuator after the selected magazine has moved properly to transfer position.

In order that the invention may be clearly understood reference is made to the accompanying drawings which illustrate by way of example the embodiments of the invention and in which:

Fig. 1 is a side elevation of a loom having the invention applied thereto,

2

Fig. 2 is an enlarged plan view of the weft replenishing mechanism looking in the direction of arrow 2, Fig. 1.

Fig. 3 is a vertical section on a reduced scale on line 3—3, Fig. 2 indicating the manner in which the several magazines can move independently of each other to place their lowest bobbins in a common transfer position.

Fig. 4 is a view similar to a part of Fig. 3 but with the magazines broken away to indicate the positions of their supports.

Fig. 5 is an enlarged detail plan view looking in the direction of arrow 5, Fig. 1, showing part of the magazine operating mechanism.

Fig. 6 is a vertical section on line 6—6, Fig. 5.

Fig. 7 is a vertical section on line 7—7, Fig. 1, showing details of the selector mechanism.

Figs. 8 and 9 are enlarged vertical sections on lines 8—8 and 9—9, respectively, Fig. 7.

Fig. 10 is an enlarged section on line 10—10, Fig. 1.

Fig. 11 is a view of the weft replenishing mechanism as seen from the center of the loom and looking in the direction of arrow 11, Fig. 2, and

Fig. 12 is a view similar to a part of Fig. 2, parts being in section, to illustrate the supports for the magazines which are omitted.

Referring more particularly to Fig. 1, the loom frame 1 supports top and bottom shafts 2 and 3, respectively, which in the present instance are connected in timed relation by a gear 4 on the top shaft meshing with a gear 5 twice its size on the bottom shaft. The loom lay 6 is reciprocated

35 backwardly and forwardly in usual manner by means of top shaft driven connectors one of which is shown at 7. The lay has a shuttle box 8 to receive any one of several shuttles with which the loom operates. In the present instance it is assumed that the loom is operating with four shuttles and that the previously mentioned weft

40 replenishing mechanism is made with four separate magazines. The lay is provided with a bunter 9 for cooperation with a transfer latch 10 pivoted on a transference arm 11.

The loom is provided with a stationary horizontal stud 12 on which is mounted an actuator lever 13 operated by a cam 14 on the bottom shaft 3. This lever 13 has a complete operation every second beat of the loom and is provided with a dog 15 for the purpose of rocking a setting lever 16 also pivoted on the stud 12 but normally at rest. Lever 16 is provided with a lug 17 under

50 which the dog 15 is directed by any one of four deflectors 18 mounted on lever 16. These deflectors are ordinarily in non-deflecting position so that the dog can rise and fall without connection with the lever 16. The deflectors are moved to deflecting position by a solenoid 19 con-

trolled by an electric weft detector D at the re-plenishing side of the loom.

Secured to stud 12 is a small stand 20 to the lower end of which is pivoted a lever 21 attached by a connector 22 to the shuttle boxes (not shown) at the opposite end of the loom. In the present instance there will be four of these shuttle boxes as is usual in many four-color weft replenishing looms. Stand 20 has a rearwardly extending horizontal arm 23 on which a bell crank lever 24 is pivoted. This lever is connected by rod 25 to lever 21 and by a second rod 26 to the gang of deflectors 18. As the shuttle boxes at the opposite end of the loom shift, the levers 21 and 24 are rocked to assume any one of four positions, one effect of which is to locate the deflector 18 corresponding to the actively placed shuttle box in register with the dog 15.

The forward end of lever 16 is connected to an upright rod 30 connected to a setting head 31 pivoted on a fixed stud 32. This head 31 is provided with a shuttle position detector 33 and a latch lifter 34. Whenever a weft replenishing operation is to occur dog 15 will be moved under lug 17 by one or another of the deflectors 18 and rod 30 will be raised to move the shuttle position detector 33 rearwardly to perform its usual function of determining whether or not the shuttle in box 8 is properly placed for a weft replenishing operation. At the same time latch 18 is moved upwardly into the path of bunter 9 for the purpose of operating the transfferer arm 11. The setting head 31 rocks when the lay is in rearward position so that the raised latch 18 will be engaged by the bunter of the advancing lay. In the present instance the shuttle in the box is indicated at S1 and carries the usual bobbin 35 which will be pushed downwardly through a slot 36 in the lay by action of the transfferer arm 11.

The matter thus far described may be of usual construction and operate in the ordinary manner and for further description reference may be had to prior Patents Nos. 1,766,895 and 1,803,181.

The weft replenishing mechanism forming an important part of the present invention is designated generally at W and includes several frame members which are shown more particularly in Fig. 11. The principal frame member F1 has a foot 40 secured to a part of the loom frame I at the forward part of the weft replenishing mechanism and has also a brace 41 which is secured to the loom frame. Fastened to and extending upwardly from the frame F1 is a second frame F2 which supports part of the operating mechanism as will be described hereinafter. Another frame F3 is secured as at 42 to the loom frame and supports a fourth frame F4, see for instance Figs. 1, 2 and 11. The loom arches 43 are shown herein as supported by the frame F3. The frames F1-F4 may be considered collectively as comprising framework for the weft replenishing mechanism.

The weft replenishing mechanism W is in the present instance adapted for supplying four different kinds of bobbins held in magazines M1, M2, M3 and M4 arranged one behind the other in the loom. The frontmost and rearmost magazines M1 and M4 are somewhat similar except of opposite hand and the other two magazines M2 and M3 are between the outside magazines and are of somewhat similar construction.

Magazine M1 has a bobbin butt guiding frame 50 and a bobbin tip guiding frame 51 connected to it by tie rods 52. Each frame 50 and 51 is

made with a slot as will be apparent from Fig. 2 to receive the corresponding parts of the bobbins B1 in magazine M1. The lower part of magazine M1 is made with its guides inclined downwardly and rearwardly and provision is made for supporting the lowest bobbin in discharge position. This provision may be a yielding butt support 53 and a yielding tip support 54. These supports are indicated on the drawing but are not set forth in detail since they follow the general pattern of supports of this type customarily found in weft replenishing mechanisms. The upper part of magazine M1 has secured thereto a support 56 which is shown as a metallic bar of rectangular cross section leading rearwardly from magazine M1 to a hub 57 mounted on a stud 58 horizontally disposed and extending laterally from the frame F1.

The rear magazine M4 has bobbin butt and tip guiding plates similar to those already described for magazine M1 but of the opposite hand and has its upper part attached to a support bar 59 leading forwardly to a hub 60 also pivotally mounted on stud 58. The supports 56 and 59 extend in opposite directions from the stud 58 and can move independently of each other with their corresponding magazines M1 and M4.

Magazine M2 is provided with butt and tip guiding frames 65 and 66, respectively, connected by tie rod 67. The upper part of magazine M2 is connected to a support bar 68 leading to a hub 69 which is pivoted on a stud 70 secured to and extending laterally from the frame F1 and parallel to stud 58. The lower end of magazine M2 is also provided with yielding supports for the butt and tip of the lowest bobbin in it, that is, the bobbin in discharge position.

The magazine M3 is somewhat similar to magazine M2 except that it is generally of the opposite hand and has a support 72 secured to the lower part thereof and swingable about a third stud 73 secured to and projecting laterally from frame F1 and parallel to the other two studs 58 and 70. The framework is provided with stops 74 for engagement with the supports 56, 59, 68 and 72 to limit upward movement of the magazines.

The lowest bobbins in the magazines are designated at D1, D2, D3 and D4, these bobbins being in discharge position with respect to their magazines and moving with the latter. As shown in Fig. 3 the magazines are movable about their centers in such manner that their bobbins in discharge position come to a common transfer position which is designated at P. Thus, the magazines M1 and M2 can be swung in a counter-clockwise direction, Fig. 1, around their respective centers and the other two magazines M3 and M4 swing in a clockwise direction around their centers, the magazines being so designed that each magazine can move to transfer position without interference on the part of the others when the latter are in their normal position. From Fig. 12 it will be seen that the supports 56 and 72 move more or less in the same vertical plane but are far enough apart vertically so that each support can move through its range of motion without interference with the other support, and this is true also of the supports 59 and 68.

The frame F1 is provided with adjustable stops 75 for engagement with the supports 56, 59, 68 and 72. These supports limit rocking movement of the several magazines to their respective transfer positions when the magazines are moved by their operating mechanisms.

The operating mechanism for the magazines is mounted partly on the frame F2 and partly on frame F4. Operating levers 76, 77, 78 and 79 pivoted on frame F2 are provided, respectively, for the magazines M1—M4 and are attached to the magazines by rods 80, the lower ends of which are connected to the corresponding supports of the associated magazines. Each of the levers 76—79 is also connected to a generally horizontally extending rod, these rods being indicated respectively at 81, 82, 83 and 84. As viewed in Fig. 1 for instance the right hand ends of these rods pass through a fixed guide support 85 and each of the rods 81—84 has the right hand end thereof surrounded by a giveaway spring 86 located between a nut 87 on the rod and the left hand down-bent end 88 of an operator 89. Each operator has the right hand end thereof connected to a guide rod having secured to the right hand end thereof a collar 91 provided with the guide pin 92 which passes through a guide plate 93. The guide rods are shown at 94, 95, 96 and 97, and correspond respectively to rods 81—84. The guide pins 92 are spaced from their rods and serve to prevent angular motion of the latter so that the operators 89 will be held in the correct upright position as suggested for instance in Fig. 1. Each of the guide rods is surrounded by a positioning spring 98 interposed between the guide 93 and the down-bent right hand end 99 of the associated operator 89.

The springs 98 normally exert a force to the left as viewed in Fig. 1 to maintain their operators 89 in normal position with the down-bent ends 88 of the operators exerting a force to the left on collars 100 secured to the rods 81—84. The springs 98 therefore act to hold the magazines normally in raised non-transferring position. When any operator 89 is moved to the right, Fig. 1, the corresponding magazine will be swung around its axis by a force transmitted through the giveaway spring 86, and if the magazine should engage its stop 75 before completion of the movement of the operator to the right the giveaway spring 86 will be compressed to absorb the excess motion without placing undue strain on the magazine.

It may be desirable to supplement the springs 98 corresponding to magazines M2 and M3 by additional means to hold these magazines in their normal raised position. Such a means may include a spring 101 anchored at one of its ends to the framework at 102 and at its other end to the support for magazine M2, as at 103. A similar spring 104 may be used for magazine M3, see Fig. 1.

The actuator mechanism for the magazines is mounted principally on frame F4 and includes a rod 105 mounted for horizontal sliding in the upper part of frame F4. This rod has secured thereto an actuator hook or head 106 to the left of the down-bent ends 99 of the operators 89 as viewed for instance in Fig. 1. Rod 105 has a collar 107 secured thereto by a pin 108, see Fig. 9. The collar is provided with a groove 109 which receives the upper forked end 110 of a positioner 111 secured by set screw 112 to a second horizontal rod 113 slidably mounted in frame F4 preferably parallel to rod 105.

Part of the rod 105 is surrounded by a sleeve 115 on which is secured an actuating head 116 connect at 117 to the upper end of an actuator rod 118 which extends downwardly and is pivotally connected to a rearwardly extending arm 119 of the setting lever 16. In the present

instance the collar 107 has secured thereto two parallel rods 120 and 121 which extend through and have sliding engagement with the head 116. Whenever operating rod 118 is depressed by rocking of lever 16 the actuator head 116 will be rocked in a clockwise direction as viewed in Figs. 8 and 9 to turn the collar 107 and rod 105 in a direction to move head 106 to the right or against the right hand downturned ends 99 of the operator 89, Fig. 1. The sleeve 115 has a collar 124 secured thereto to limit motion of the sleeve to the left, Fig. 10, and the head 116 is limited in its motion to the right, Fig. 10, by a bearing 125 in the upper part of the frame F4. The head 116 therefore always moves in the same actuating plane regardless of the longitudinal position of the rod 105.

The selector mechanism is also mounted principally on frame F4 and includes the previously mentioned positioning member 111 and a positioning lever 130 connected by link 131 to rod 113. Lever 130 is pivoted on a stud 132 mounted on a small stand 133 secured to and extending to the left of frame F4, see Fig. 10. Lever 130 is connected to a positioning rod 135 which extends downwardly and is pivotally connected to an arm 136 of previously described lever 24. A tension spring 137 is connected at its lower end to rod 135 by a collar 138 and has its upper end engaged with a hook 139 fixed with respect to the stand 133.

Whenever lever 24 is moved due to a shifting of the shuttle boxes at the opposite end of the loom the vertical position of rod 135 is changed and there will be a corresponding rocking of lever 130 so that it can occupy either the position shown in full lines or the positions shown in broken lines in Fig. 10. When lever 130 rocks it acts through the positioner 111 to slide the rod 105 and therefore the actuator head 106, causing the latter to register with the operator 89 corresponding to the shuttle box in active picking position. The actuator 106 is therefore kept in register with the operating mechanism for the magazine which corresponds to the active shuttle.

It is believed that the operation of the invention will be understood from the foregoing description. Whenever the detector D indicates weft exhaustion in shuttle box 8 the solenoid 19 is energized to move into deflecting position the deflector 18 corresponding to the shuttle box assigned to the shuttle in box 8, and as the operating lever 13 is rocked in a clockwise direction, Fig. 1, the setting lever 16 is swung around stud 12 to set the loom for a replenishing operation by movement of the latch 10 into the path of the bunter 9 and by movement of the shuttle position detector 33 in a rearward direction, to the right, Fig. 1. At the same time actuator rod 118 is depressed so that the head 106 is rocked to the right, Fig. 1, to move the operator 89 registered therewith to the right and cause rocking of the associated magazine to move its lowest bobbin in discharge position to transfer position indicated at P in Fig. 3. When the bunter 9 engages the latch 10 transfer arm 11 is rocked in usual manner to transfer the bobbin in transfer position into the shuttle in shuttle box 8. The transfer arm may conveniently be pivoted on a stud 140 fixed with respect to the frame F4.

During movement of the selected magazine to transfer position the associated operator 89 will be moved to the right, Fig. 1, causing compression of the corresponding spring 98. If angular motion of the actuator head 106 should be slightly

more than that required to move the magazine to transfer position there will be a compression of the corresponding spring 86 when the magazine engages its stop 75. The cam 14 is so shaped that lever 16 will be held in its setting position long enough to hold the actuator head 106 in its operating position, shown in broken lines in Fig. 9, until the bobbin transferring operation can be completed and the transferrer arm 11 started upward in usual manner on its return stroke. Dog 15 will then descend to permit return counter-clockwise rocking of lever 16 to its normal position which will result in movement of the shuttle position feeler 33 away from its detecting position and will permit the latch 10 to fall to non-transferring position and will permit upward motion of the actuator rod 113 to return the actuator head 106 to its normal operating position shown in full lines in Fig. 9. This completes the bobbin transferring operation, return of the actuator head 106 to its normal position by the spring 98 registered therewith being accompanied by return of the previously activated magazine to its normal raised non-transferring position.

In the description of operation given above it was assumed that lever 136 and the actuator head 106 were in the full line position shown in Fig. 10, but it will be understood that the operation will be the same if the lever and head 106 are in any of the broken line positions shown in Fig. 10, the only difference being that the magazine actuated will be the one corresponding to the position of the lever and head.

From the foregoing it will be seen that the invention sets forth the weft replenishing mechanism having at least three separately movable magazines so mounted that the lowest bobbin in each magazine can move to a common transfer position by swinging of the magazines. The magazines are normally in non-transferring position and are so disposed that each can move to transfer position independently of the other magazines. Also, the supports for the magazine, such as the bars 56, 59, 68 and 72, are arranged so that each can have a necessary range of motion without interference on the part of any other support, this feature being more particularly concerned with the lower supports for the inner magazines M2 and M3 which are under the upper supports for magazines M1 and M4, respectively. It will further be seen that each of the operating mechanisms includes two springs and two substantially rigid parts, spring 98 normally tending to restore its magazine to normal non-transferring position and spring 86 yielding in the event that the actuator head 106 should move the operating mechanism a short distance after the called magazine is against its stop 75. The rigid parts, 81 and 89, transmit force under action of spring 98 in a given direction, to the left in Fig. 6, to rock the magazine back to normal position after a transfer. Spring 86 normally holds the rigid parts in force transmitting relation and is strong enough to transmit the force required to rock the magazine to transfer position, yielding only upon excess motion of head 106. Also, the selector and actuator mechanism includes the actuator head 106, the sliding rod 105 to which it is secured, the grooved collar 167, and the yoke positioning member 111, and the lever 130 which is moved in response to shifting of the shuttle boxes and angular movement of levers 21 and 24. Also, each of the inner magazines M2 and M3 swings about an axis spaced from a line

passing through the transfer position and the common axis for the magazines M1 and M4.

Having now particularly described and ascertained the nature of the invention and in what manner the same is to be performed, what is claimed is:

1. In a weft replenishing loom having a lay, a weft replenishing mechanism provided with four reserve bobbin magazines arranged in front to back order in the loom and down each of which bobbins move by gravity to a low discharge position in the magazine, means for each magazine yieldingly holding the latter in normal position with the bobbin in discharge position therein spaced from a transfer position from which the bobbin can be transferred to the lay, a common pivotal support for the frontmost and rearmost magazines located so that either of these two magazines can swing about said pivotal support to move the bobbin in discharge position therein to said transfer position, the other two magazines being located between said frontmost and rearmost magazines, a separate pivotal mounting for each of said other two magazines located so that either magazine can swing to move the bobbin in discharge position therein to said common transfer position, operating mechanism for each magazine, actuator means movable to register with the operating mechanism, one at a time, and effective when operating to move the magazine registered therewith to move the bobbin in discharge position therein to said transfer position, and selector means to move the actuator means into register with any one of said operating mechanisms.
2. In a weft replenishing loom having a reserve bobbin magazine normally in non-transferring position but movable to bobbin transfer position, an actuator having an actuating movement to move the magazine to transfer position, a stop to limit movement of the magazine by the actuator beyond said transfer position, and operating mechanism for actuation by the actuator operatively connected to the magazine and including two substantially rigid parts and two springs, one of said springs normally urging one of said rigid parts in a given direction and causing said one part in cooperation with the other of said rigid parts to hold the magazine in normal non-transferring position, said one part being in the path of the actuator to be moved by the latter on an actuating movement thereof to overpower said one spring and cause the operating mechanism to move the magazine against said stop, and the other spring being operatively interposed between said rigid parts normally holding said parts in position to cause said other part to be moved by said one part when the latter is moved in said given direction but yielding upon engagement of the magazine with the stop to permit relative motion of said rigid parts in the event the actuator continues to move after the magazine engages the stop.
